MOUNTING STRUCTURE

Louis H. Von Ohlsen, New Haven, Conn., assignor
to The Safety Car Heating and Lighting Com-
pany, Inc., a corporation of Delaware

Application August 6, 1941, Serial No. 405,596

8 Claims. (Cl. 105—133)

This invention relates to railroad car construction, and more particularly to an equipment unit and a mounting construction for securing the unit to a railway passenger car.

One of the objects of this invention is to provide an equipment unit for a railway car made up of standard elements and secured together as a unit for attachment to the car in such a manner that the individual elements of the unit may be detached as desired for purposes of repair or replacement. Another object is to provide a mounting construction for such an equipment unit by which the unit can be attached to the floor structure of the car. Another object is to provide a mounting construction of the above nature characterized by simplicity, rigidity and durability and capable of supporting the equipment unit without transmitting vibrations therefrom to the car structure. Other objects will be in part apparent and in part pointed out herein-after.

The invention accordingly consists in the features of construction, combinations of elements, and arrangements of parts as will be exemplified in the structure to be hereinafter described and the scope of the application of which will be indicated in the following claims.

In the drawings, in which is shown one embodiment of my invention,

Figure 1 is a side elevation of a railway passenger car provided with my equipment unit and its mounting;

Figure 2 is an enlarged exploded isometric view of my equipment unit and its mounting, a portion of the mounting being broken away;

Figure 3 is an enlarged fragmentary elevation of a portion of the mounting;

Figure 4 is a sectional elevation taken along the line 4—4 of Figure 1; and,

Figure 5 is a sectional elevation taken along the line 5—5 of Figure 1.

Similar reference characters refer to similar parts throughout the various views of the drawings.

Modern railway passenger cars are often equipped with a unitary power system for operating the lighting system, air conditioning apparatus and auxiliaries. Such a power unit may include a generator, and where the car includes air conditioning equipment, the generator is coupled to the compressor in the air conditioning apparatus. It has been found convenient to use standard generators and compressors, but as these individual elements of the power unit are heavy, difficulties are encountered in supporting them

on the car. The power unit, for purposes of accessibility and by reason of space limitations is usually suspended from the floor structure of the car, which causes problems of vibration transmission, alignment of the several elements of the power unit installation, and repair or replacement. It is accordingly another object of this invention to provide a mounting or chassis for such a power unit which obviates the above difficulties and disadvantages.

This application is related to my copending application, Serial No. 405,597, filed herewith, and discloses in general the same mechanism as that more particularly described in my said copending application. My copending application is directed particularly to the operating relationship of the various portions of the apparatus and to the control, whereas the present application is directed particularly to the mounting arrangement of the structure. My copending application is therefore incorporated herein and reference may be had thereto for details.

In Figure 1, I have shown a railroad passenger car 10 having conventional floor structure generally indicated at 11, to the side of which is attached my power unit chassis generally indicated at 12, to which a power unit, generally indicated at 13, is detachably secured. Power unit 13 includes an internal combustion motor 14, a generator 15, and a compressor 16, all as will be described in greater detail hereinbelow.

As shown in Figure 2, chassis 12 comprises a pair of elongated channel members 17 and 18, which are secured together in spaced, parallel relation by a pair of Z-beams 19 and 20. Beams 19 and 20 are preferably secured to channels 17 and 18 by welding, and may be attached to the channels near the ends thereof. Through the provision of the channels, which are U-shaped in cross section, and the Z-beams, substantial rigidity is imparted to the chassis. Thus channels 17 and 18 extend longitudinally of car 10 (Figure 1) and underlie the car structure 11 which, as shown in Figure 5, comprises parallel spaced sills or channel members 11a and 11b from which chassis 12 may be suspended in a manner to be described.

Adjacent each corner of chassis 12 (Figure 2) is secured a hanger generally indicated at 21, which includes a side flange 23, which lies against the web 18b of channel 18 when the hanger is secured in position. Hanger 21 is secured to channel 18 by a pair of bolts 22 which pass through registering holes in hanger flange 23 and channel web 18b. Referring back to Figure 2, hanger 21 is provided with an upwardly and

illustratively inwardly extending flange 27 provided with a hole 28, and this flange 27 is rigidly reinforced by a pair of webs 29 and 30 which are integrally formed with the flange. As shown, these webs lie on opposite sides of hole 28. Hanger 21 is also preferably provided with a stiffening web 31 which is integral with the inner and lower sides of hanger flanges 23 and 27, respectively. It will thus appear that hanger flange 27 is rigid with relation to the rest of the hanger, so that its under surface is rigidly held to a horizontal plane.

Chassis 12 is suspended from car floor channels 11a and 11b (Figure 5) by hangers 21. As shown in Figure 3, hanger flange 27 overlies the lower flange of floor channel 11b, and interposed between hanger flange 27 and the flange of the floor channel is a rubber pad 32 which transfers the weight of chassis 12 and unit 13 (Figure 1) to the car floor structure 11. A bolt 33 (Figure 3) extends through hole 28 in hanger flange 27, and also through the lower flange of the car channel to restrain excessive relative movement between the hanger and the car floor channel. The head of bolt 33 is insulated by a rubber washer 34 from hanger flange 27 so as to avoid transmission of vibration. Bolt 33 is held in proper position by a nut 35 threaded on its lower end. Preferably a metal washer 36 is disposed between the bottom of hanger flange 27 and the top of rubber pad 32, another washer 37 preferably being interposed between the head of bolt 33 and the top of rubber washer 34.

It will now appear that chassis 12 (Figure 1) and power unit 13, the total weight of which is substantial, is directly supported on live rubber by the car floor structure 11 in such a manner that vibration resulting from operation of the power unit is not transmitted to the car floor structure, and accordingly to the car.

Referring back to Figure 2, channel 13 of chassis 12 is provided with a pair of spaced blocks 38 and 39 directly over which are a pair of holes 40 and 41 extending through web 43b of the channel. Chassis channel 11 is similarly provided with blocks 42 and 43 and holes 44 and 45. All of these blocks are preferably welded to their respective channels and, as will be pointed out hereinbelow, provide supporting surfaces for the suspension of internal combustion motor 14. Chassis channel 13 has welded thereto another pair of blocks 46 and 47 underlying holes 48 and 49 extending through the web 43b of the channel. Channel 11 is also provided with another pair of supporting blocks 50 and 51 and adjacent holes 52 and 53. This latter set of blocks 46, 47, and 50, 51, provide, as will be described in detail below, supporting surfaces from which generator 15 and connected compressor 16 are suspended.

Motor 14 and generator 15 may be standard units and preferably are provided with a driving connection generally indicated at 54, comprising a driving disc 55 provided with a plurality of pins 56 adapted to be inserted in rubber-lined holes 57 drilled in a driven disc 58. Driving disc 55 is secured to one end of a shaft 59 which is driven by motor 14. Driven disc 58 is secured to the end of armature shaft 60 of generator 15. Thus motor 14 and generator 15 may readily be connected or disconnected merely by moving one axially toward or away from the other.

Motor 14 has secured to one end thereof a pair of supporting brackets 61, and to the top

thereof a mounting plate 62 (see also Figure 5) the latter of which is adapted to be secured to a tubular supporting unit generally indicated at 63 (Figure 2). Supporting unit 63 preferably comprises a heavy elongated tube 64 on the opposite ends of which are welded supporting plates 65 and 66. Plate 65 has a wide slot 67 cut therein to form a pair of spaced legs 68 and 69. Plate 66 is similarly provided with a slot 70 and spaced legs 71 and 72. Each of the legs on plates 65 and 66 is provided with a hole 73, and the spacing between the legs, for example legs 71 and 72, is identical with the spacing between supporting blocks 42 and 43, for example, so that when supporting member 63 is installed on chassis 12, legs 68 and 69 rest respectively on blocks 38 and 39, while legs 71 and 72 rest respectively on blocks 42 and 43. When the legs are positioned on their respective blocks, holes 73 in the legs register respectively with channel holes 40, 41, 44 and 45, so as to receive bolts 74 (Figure 5). Bolts 74 have nuts 75 threaded on their outer ends which press washers 76 against the side channels 11 and 13 of chassis 12 and accordingly securely hold supporting member 63 rigidly in place on the chassis.

Supporting member 63 (Figure 2) also has welded thereto a pair of L-shaped brackets 77 and 78, the bottom horizontal flanges 77a and 77b of which are drilled with holes 79 which register with holes 30 on mounting plate 62 to receive bolts 81 (Figure 5) by which motor 14 is secured to brackets 77 and 78 and accordingly to supporting member 63. Preferably the supporting member is bolted to the motor and both are installed in their operative position. This is done by lifting the assembled support 63 and motor 14 upwardly into chassis 12 so that blocks 43 and 39, for example, pass through slots 70 and 67. When support 63 has been sufficiently raised so that it and motor 14 can be moved longitudinally of chassis 12 without interference by any of the blocks, support 63 is then moved longitudinally of the chassis until the legs are in alignment with their respective blocks. When motor 14 is in this position, its brackets 61 abut web 19a of Z-beam 19, and holes 61a in brackets 61 register with holes 19b in the Z-beam to receive securing bolts (not shown). It will now appear that Z-beam 19 and support 63 securely suspend motor 14 from chassis 12.

Still referring to Figure 2, generator 15 has welded thereto in spaced relation a pair of angle beams 82 and 83 (see also Figure 4). Each of these beams has an arcuate portion cut from the vertical flange thereof as at 82a on beam 82 so that the beams fit the curvature of the generator casing and accordingly provide adequate area for welding purposes. Angle beam 82 has secured at the opposite ends thereof plates 84 and 85, provided with holes 86 and 87, respectively. Beam 83 is similarly provided with end plates 88 and 89 through which holes 88 and 89 extend respectively.

Angle beams 82 and 83 are spaced apart when welded to generator 15 by a distance equal to the distance between supporting blocks 50 and 51, for example, on chassis channel 11, so that when the generator and its supporting angle beams 82 and 83 are installed in operative position, beam plates 84 and 85 rest on supporting blocks 50 and 51, while end plates 88 and 89 of beam 83 rest on supporting blocks 47 and 51. When the beams are in this position, channel holes 53 and 52 register with beam plate holes 86 and 87 and chan-

nel holes 49 and 53 register with beam plate holes 98 and 91. Each pair of registering holes receives a nut, bolt and washer similar to nut, bolt and washer 74, 75 and 76 shown in Figure 5.

It will now appear that generator 15, together with connected compressor 16, is installed on and secured to chassis 12 in much the same manner as that described above with respect to motor 14. It should also be noted that either the motor or the generator may be installed first, as regardless of which is first fastened in place, the other may readily be lifted in and then moved longitudinally of the chassis until a driving connection is effected by coupling 54 by the entry of driving pins 56 into holes 57. To make certain of the alignment of the axes of driving shaft 59 and armature shaft 60, the upper surfaces of the several supporting blocks on chassis channels 17 and 18 are all machined in one operation so that such surfaces lie in the same horizontal plane. This assures alignment of the axes of motor 14 and generator 15.

It will now appear that either motor 14 or generator 15 may be individually installed on chassis 12 or detached therefrom by tightening or loosening the few bolts by which each is secured to the chassis. It will also appear that the chassis with the motor and generator secured thereto can also be installed on or detached from car floor structure 11 (Figure 1) as a unit through the manipulation of bolts 22 which secure chassis 12 to hangers 21 (Figure 2).

Accordingly I have provided a railway car equipment unit, together with structure for mounting the unit on a car, which attains in a thoroughly practical and efficient manner the several objects referred to above.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In a vehicle construction, in combination, a frame construction comprising a pair of beam members, a plurality of inverted-L bracket members attached to said beam members with each of said bracket members presenting a downwardly extending supporting portion, a substantially rectangular frame having longitudinal members extending along and removably attached to said supporting portions, a bridge member extending across said frame and related at its ends to said longitudinal members for longitudinal and then vertical detaching movement, a motor rigidly attached to said bridge member to be supported thereby, an electric generator having a plurality of bridging support members attached at their ends to said longitudinal members, and means constituting a detachable mechanical coupling between said motor and said generator.

2. In railroad car construction, in combination, a car having a floor structure including a pair of spaced parallel supporting flanges, a plurality of inverted-L brackets each having a horizontal portion resting upon one of said supporting flanges and a vertical portion extending downwardly therefrom, a removable frame attached to the vertical portions of said brackets, a plurality of ledge portions having upper surfaces which are in a single horizontal plane and ex-

tending inwardly with respect to the sides of said removable frame, a plurality of bridge members extending across said removable frame and resting upon said ledge portions, and a motor attached to one of said bridge members and having integral flange means rigidly bolted to said removable frame.

3. In apparatus of the character wherein electric power is delivered to a load from a power unit which includes a generator driven by a motor and wherein the entire power unit may be readily removed or either the motor or the generator may be independently removed, the combination of, means constituting a reliable support means, a supporting frame attached to said support means and including a pair of substantially parallel horizontal side members and a pair of end members, a bridge member extending across said supporting frame and having end means interengaging with said side members and adapted to be disengaged by movement of said bridge member longitudinally of the supporting frame, a motor rigidly attached to said bridge member and having integral flange means rigidly attached to one of said end members to thereby prevent longitudinal movement of said bridge member with respect to said supporting frame.

4. In apparatus of the character wherein electric power is delivered to a load from a power unit which includes a generator driven by a motor and wherein it is desirable to suspend the entire power unit for ready removal or for the removal of either the motor or the generator, the combination of, a substantially rectangular rigid supporting frame formed of four channel members attached together and so positioned that the flanges on the channel members extend outwardly with respect to the supporting frame, bracket means extending down along and attached to the inside surfaces of the mounting frame and presenting unobstructed plane surfaces which lie flat against the co-operating surfaces of the supporting frame so that when the attaching means between the bracket means and the supporting frame are removed the supporting frame is readily moved downwardly free of the bracket means, a removable bridge member extending across said supporting frame and removably attached at its ends to the side members of the supporting frame, a motor rigidly carried by said bridge member, a generator having bridging brackets attached thereto and said brackets being in turn removably attached to the opposite sides of said supporting frame, and a detachable mechanical coupling between said motor and said generator and adapted to be separated by merely causing relative longitudinal movement between said generator and said motor.

5. In railroad car construction, in combination, a car having a floor structure including spaced parallel sills having outwardly extending horizontal flanges, a frame-like chassis, a plurality of hanger members secured to said chassis and having inwardly extending flanges, means forming a vibration absorbing connection between said hanger flanges and said sill flanges whereby said hanger flanges embrace said sills to suspend said chassis therefrom, a power unit, and means for detachably securing said power unit to said chassis.

6. In railroad car construction, in combination, a car having a floor structure, a chassis secured to said floor structure and including a pair of spaced parallel supporting elements, a pair of spaced blocks secured to each of said supporting

elements, each of said blocks having a horizontal supporting surface, said horizontal supporting surfaces all lying in the same horizontal plane, a bridge member having a pair of spaced supporting feet at each end thereof, the spacing between said feet being the same as that between said blocks and the space at the side of the blocks being unobstructed so that the bridge member may be moved vertically with the respective feet moving at the side of the blocks, each pair of feet being adapted to rest on one pair of blocks, means for detachably securing said bridge member in position on said chassis, thereby to hold said feet in place on said blocks, and a power unit secured to said bridge member whereby the power unit may be removed by detaching said means and then moving the power unit and bridge member longitudinally of said parallel

members so that each of said feet is moved to the side of its block and then the power unit may be lowered from said chassis.

7. Apparatus according to claim 6 wherein there is provided a driven member, means forming a detachable connection between said driven member and said power unit and adapted to be separated by causing relative longitudinal movement between said power unit and said driven member, and means for detachably securing said driven member to said chassis.

5 8. Apparatus according to claim 2 wherein there is provided a generator, means forming a detachable coupling between said motor and said generator, and means for attaching said generator to another of said bridge members.

10 15 LOUIS H. VON OHLSEN.
